UNITED STATES PATENT OFFICE.

CLARK S. COMSTOCK, SR., OF EAST ORANGE, NEW JERSEY.

GARMENT-LOOP.

1,194,716.

Specification of Letters Patent. Patented Aug. 15, 1916.

Application filed March 17, 1916. Serial No. 84,834.

To all whom it may concern:

Be it known that I, CLARK S. COMSTOCK, Sr., a citizen of the United States of America, residing in East Orange, in the county 5 of Essex and State of New Jersey, have invented certain new and useful Improvements in Garment-Loops, of which the following is a specification.

This invention relates to garment loops 10 or the like, and aims to provide certain improvements therein.

Such garment loops are primarily intended to be carried at the end of a suspender strap, and are usually designed to engage 15 a button upon the trousers. They are largely used in the manufacture of overalls and similar cheap garments, and it is very desirable that they shall be capable of being manufactured as economically as possible. 20 Such loops are preferably made of a single piece of wire usually shaped to form a button recess and a strap recess, the ends of the wires being connected in some way to hold the parts of the loop together.

According to the present invention I provide 25 a construction which may be manufactured from a single piece of wire, and in which great rigidity and strength is secured with the use of comparatively small gage 30 of wire. According to this invention I may also secure a loop in which the button recess is capable of expansion to receive the head or shank of different sizes of buttons and retain the buttons securely in place without 35 sacrificing either simplicity of construction or strength of structure.

The invention includes certain other features of improvement which will be herein-after more fully pointed out.

Referring to the drawings which illustrate 40 several forms of the invention, Figure 1 is a front or face view of a loop, embodying the invention. Fig. 2 is a section on the line 2-2 in Fig. 1. Fig. 3 is a section on the line 3-3 in Fig. 1. Fig. 4 is a view similar to Fig. 1 of a slightly modified construction. Fig. 5 is a section on the line 5-5 in Fig. 4. Fig. 6 is a section on the line 6-6 in Fig. 4. Fig. 7 is a view similar 50 to Fig. 1 of a still further modification.

Referring first to Figs. 1 to 3, let A indicate the loop as a whole which is shown in this figure as having a strap recess B and a button recess C. In the construction illustrated the loop is shown as completely 55 formed of a single piece of wire without the addition of ferrules or other parts. An important feature of construction is the fastening of the ends of the wire to other parts of the structure by which strength and 60 rigidity are secured with a small gage of wire.

In the construction shown in Figs. 1 to 3, the strap recess B is formed by an upper portion a and two lower portions b b'. The 65 button recess C is formed of two side portions d d' which join the portions b b'. In these figures the wire starts at a point e, then is extended to the left to form the portion b, thence upwardly and to the right to 70 form the portion a, thence downwardly and to the left to form the portion b', then downwardly to form the portion d', and thence upwardly to form the portion d to a point f. The end e is fastened to the upper 75 part of the portion d' preferably by bending it directly around such portion, and the end f is connected to the portion b, preferably also by bending it around such portion. It will be observed that by this construction both ends of the wires are connected at what may be termed the neck of 80 the loop, that is to say, that portion which approximately coincides with the juncture between the upper or strap-receiving portion and the lower or button-receiving portion. It will also be observed that the ends are not connected together in the sense that they are looped around each other, but that 85 on the contrary each loop is connected to what may be called a part of the body of 90 the wire. The result is that between the two upper portions of the button-receiving portion there is a cross piece of wire indicated at g which serves to connect the two parts 95 of the button-receiving portion and the two parts of the strap-receiving portion. In the construction of Figs. 1 to 3 this practically forms a closed strap-receiving portion and a closed button-receiving portion, and if 100

the ends of the wire are tightly clamped in place, as is shown in Figs. 1 to 3, a construction of great rigidity is formed. This enables me to use a much finer wire than is now customary and still secure a more rigid and strong construction than has heretofore been possible. The result is a very considerable saving in the cost of manufacture, and the production of a loop which is of great strength and durability. It is preferable to form a shoulder h on the inner end of the portion b which shoulder provides a stop against which the loop f may rest, so as to prevent any possibility of a separation of the portions d d' .

In the construction of Figs. 1 to 3 the button-receiving recess C is preferably large enough to take in any sized button which the loop is intended to engage, and it is preferable to form a shank recess D in which the button is finally received, the recess being slightly constricted above it, as shown at E .

The invention is applicable with but little modification to various types of spring loop construction, some of which are shown in the drawings.

In Figs. 4 to 6 the total width of the button-receiving recess C' is less than the extreme diameter of the button which it is to engage. The result of this construction is that in order to engage a button one or the other of the sides d^2 d^3 must spring outwardly as the button is forced in between them. This outward spring is usually just sufficient to permit the button to pass into the recess, and when the side springs back, the recess is again contracted, so as to prevent accidental disengagement of the loop. According to the present invention this is easily secured by forming the eye f' so that it does not tightly bind the portion g' , but is capable of sliding along the latter to a limited extent. Preferably a stop portion h' is formed to prevent undue movement of the side d^2 whereby the latter cannot be strained beyond its elastic limit.

In Fig. 7 the invention is shown as applied to a type of spring loop in which the button-receiving recess C^2 is sufficiently large to enable it to pass over a button without being expanded, but the throat portion E^2 leading to the recess D^2 is constricted so that the button shank cannot pass through it unless it is enlarged. This enlargement takes place when the button is forced through the throat by springing out of one of the side members d^4 d^5 . This is provided for in the present construction by giving the eye f^2 the same capacity of sliding along the portion g^2 as is shown in Fig. 4. Preferably, however, the portion g^2 is made longer than in Fig. 4 in order to produce a more symmetrical and efficient structure.

As before, a stop h^2 is provided which prevents undue movement of the eye f^2 and consequently undue straining of the button-receiving portion.

In all of the constructions illustrated a cheap and strong structure is obtained. Even with the sliding connection shown in Figs. 4 to 7 it is almost impossible for the loop to be distorted out of shape by any strain to which it is put in use.

While I have shown and described several forms of the invention, it will be understood that I do not wish to be limited thereto, since various changes can be made therein without departing from the invention.

What I claim is:—

1. A garment loop having a strap-receiving portion comprising an upper bar around which the strap passes, and a lower portion lying below the first and extending substantially across the loop, and a button-receiving portion, said garment loop being formed of a single piece of wire, the ends of which are connected at the juncture of such lower portion and button-receiving portions.

2. A garment loop having a strap-receiving recess and a button-receiving recess, said garment loop being formed of a single piece of wire and said wire passing completely across the bottom of the strap-receiving recess and the top of the button-receiving recess, and permanently separating the two.

3. A garment loop having a strap-receiving recess and a button-receiving recess, said garment loop being formed of a single piece of wire, and each of said recesses being permanently closed by said wire.

4. A garment loop having a strap-receiving recess and a button-receiving recess, said garment loop being formed of a single piece of wire, and an end of said wire passing across the bottom of said strap-receiving recess and the top of said button receiving recess, and permanently separating the two.

5. A garment loop formed of a single piece of wire into a strap receiving recess and a permanently separate button-receiving recess, and one end of said wire passing across the top of said button-receiving recess and looped around the body of the wire, and the other end of said wire being connected to the body of the wire near the first end.

6. A garment loop comprising a strap-receiving recess and a button-receiving recess, said loop being formed of a single piece of wire, one end of which is carried across the point of juncture between the two recesses and is secured to the body of the loop to form a permanent separation between the two recesses, and the other end of which is secured to the body of the loop near the first end.

7. A wire garment loop having a strap-

receiving recess and a button-receiving recess, the wire at one side of the button-receiving recess having an eye, and said loop having a portion extending across the top of the button-receiving recess to permanently separate it from the strap-receiving recess to form a guide for said eye.

5

In witness whereof, I have hereunto signed my name in the presence of two subscribing witnesses.
